UNITED STATES PATENT OFFICE

FRANK ORTELL, OF NEW YORK, N. Y.

DESIGN FOR A SCARF.

Application filed October 24, 1932. Serial No. 45,538. Term of patent 3½ years.

To all whom it may concern:

Be it known that I, FRANK ORTELL, a citizen of the United States, residing at New York, New York, have invented a new, original, and ornamental Design for Scarfs, of which the following is a specification, reference being had to the accompanying drawing, forming part thereof.

The single figure now in the drawing shows one-fourth of my new design for a scarf, it being understood that the remaining sections of the design are repeated in proper relation about a center indicated by the intersection of the broken lines.

I claim:

The ornamental design for a scarf as shown and described.

FRANK ORTELL.
